UNITED STATES PATENT OFFICE.

JOSEPH DI STANISLAO, OF CAMDEN, NEW JERSEY.

COMBINATION RADIO AND PHONOGRAPH CABINET.

Application filed June 24, 1924. Serial No. 721,969.

My invention relates to combination radio and phonograph cabinets.

The objects are to provide a cabinet which will house radio and phonograph apparatus; in which access to the parts may be readily had, and in which a common horn serves to amplify the sounds coming from either the radio or phonograph recording apparatus.

10 These objects, and other advantageous ends which will be described hereinafter, I attain in the following manner, reference being had to the accompanying drawings in which—

15 Figure 1 is a front elevation of a cabinet constructed in accordance with my invention.

Figure 2 a section substantially on line 2—2 of Figure 1, the radio sound producer connection to the horn and the rear of the cabinet to the right of line 2—2 being shown in section,

Figure 3 a section on line 3—3 of Figure 1,

25 Figure 4 a fragmentary section on line 4—4 of Figure 2, and

Figure 5 a perspective view of the amplifying horn with certain parts omitted.

Referring to the drawings, 1 indicates a 30 casing of any suitable design having a sound opening 2. A partition 3 is secured in the casing adjacent its top. A horn 4 is secured to the partition and to the casing around the opening, and consists of a conduit 5 split longitudinally into sections, and an amplifying part 6 secured to the conduit. The upper end of the conduit is provided with a pair of nipples 7 which pass through partition 3, a shoulder 8 which abuts the

40 bottom of the partition and flanges 9 at opposite sides of the nipples by which the conduit may be secured to the partition. The main passage of the conduit has a pair of branch passages 10 and 11 diverging upwardly therefrom. Phonograph apparatus

45 12 is mounted on the partition 3 and has its sound box 13 connected with branch passage 10 by the tone arm 14. Radio receiving apparatus 15 has its sound producing unit 16 connected to branch passage 11. Radio receiving apparatus 15 is mounted on a drawer 17 slidable in the casing on guides 18 under partition 3. The bottom of the drawer is provided with a cut-out part 19 through

55 which conduit 5 depends. The amplifying part 6 consists of four thin flaring walls

secured to each other, to the lower end of conduit 5 as shown at 20 and to the casing around opening 2 as shown at 21. The rear of the casing is provided with doors 22 which afford access to the interior of the casing. A compartment 23 is preferably provided under opening 2 for keeping records or other articles.

By pulling drawer 17 out into the dot-and-dash line position shown in Figure 2 or opening door 22, access to the parts may be readily had. Either the phonograph or radio apparatus may be operated to produce sounds without interference from either apparatus. Batteries and other accessories required for a radio receiving apparatus may be mounted on the drawer and removed from the cabinet with the drawer as a unit.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In a cabinet provided with a casing having an opening and a partition in the upper part of the casing; a horn supporting conduit secured to the under side of the partition and depending downwardly and having a pair of upwardly diverging passages leading to its upper end adapted to be connected with sound re-producing means, and a horn part connected to the casing around the opening and to the lower end of the conduit and communicating with the passages.

2. In a cabinet provided with a casing having an opening and a partition in the upper part of the casing; a horn supporting conduit having a pair of nipples passing through the partition, and a shoulder abutting the under side of the partition for securing the conduit thereto, the conduit having a pair of upwardly diverging passages through the nipples, and a horn part secured to the casing around the opening and to the lower end of the conduit and communicating with the passages.

3. In a cabinet provided with a casing having an opening and a partition in the upper part of the casing; a horn supporting

conduit having a pair of nipples at its upper end passing through the partition, a shoulder abutting the partition and a pair of flanges at opposite sides of the nipples for securing the conduit to the partition, the conduit being provided with upwardly diverging passages through the nipples, and

split longitudinally from the point of divergence to the lower end, and a horn part secured to the lower end of the conduit and 10 to the casing around the opening.

In testimony whereof I have signed my name to this specification.

JOSEPH DI STANISLAO.
